UNITED STATES PATENT OFFICE.

HORATIO J. BREWER, OF NEW YORK, N. Y.

GALVANIC BATTERY.

SPECIFICATION forming part of Letters Patent No. 380,084, dated March 27, 1888.

Application filed October 22, 1886. Renewed September 27, 1887. Serial No. 250,844. (No model.)

To all whom it may concern:

Be it known that I, HORATIO J. BREWER, of the city, county, and State of New York, have invented a new and Improved Porous-5 Cup Battery, of which the following is a full, clear, and exact description.

The object of my invention is to provide a certain new and useful improvement in porous-cup batteries, whereby a thorough contact between 10 the electrode and the electro-negative material in the porous cup is established, and the electrode is held in a firm position and the accumulation of a coating on the electrode is prevented.

15 The invention consists of an electrode provided with inclined sides.

The invention also consists of various parts and details and combinations of the same, as will be fully described hereinafter, and then 20 pointed out in the claims.

Reference is to be had to the accompanying drawings, forming a part of this specification, in which similar letters of reference indicate corresponding parts in all the figures.

25 Figure 1 is a central sectional elevation of my improvement; and Figs. 2, 3, and 4 are sectional plan views of the electrode on the line *x x* of Fig. 1, showing varied forms of the cross-section of the electrode.

30 In the jar A, of any suitable form and size, is placed the porous cup B, in which is set the electrode C, of carbon or other material, and provided with inclined sides and resting with its base on the bottom of the cup B. The 35 upper end of the electrode C projects beyond the upper end of the jar A, and is preferably of uniform shape in cross-section and carries the binding post or clamp D, of any approved construction. The electro-negative material

40 E is placed in the said cup B, and surrounds the inclined sides of the carbon electrode C and packs against the said inclined sides. After the electrode C and the material E are placed in the porous cup B, moistened cement is poured 45 upon the material E, so as to form a cover, F, on top of the material and around the electrode C. The cement covering F is held in place on the upper end of the cup B, which is provided with indentations which are filled by 50 the cement, and thus hold the cover F firmly in position. A cover, G, is fitted on the mouth of the jar A, and through an aperture in the

same projects the straight upper end of the electrode C.

The cross-section of the electrode C may be 55 of various shapes, as shown in Figs. 2, 3, and 4, but the electrode must be provided with inclined sides. It will be seen that as the material E presses on the inclined sides of the electrode C it establishes a strong contact 60 with the said electrode, and thereby increases the efficiency of the battery. At the same time the electrode C is held in a firm position in the porous cup, as the material E and the cover F prevent a sidewise or an upward mo- 65 tion.

It will further be seen that when a battery is moved about the material E is disturbed in its position around the electrode C and shifts its contacting-point with the sides of the said 70 electrode, and as the latter is usually slightly coated on the parts not covered by the material, caused by the action of the liquid used in connection with the battery, and as the coated spots or places on the electrode form a bad 75 conductor, it is evident that when the material changes its position and comes in contact with the coated places or spots on the electrode C it will decrease the efficiency of the contact between the electrode and the material. This 80 is true only for electrodes without inclined sides; but with my electrode I obviate this difficulty, as the pressure of the material on the inclined sides of the electrode is always sufficient to scrape the coating off when the 85 material shifts its position, and thus a direct contact with the electrode is always insured.

The cement used as a cover is preferably 90 Portland cement, which is mixed with water to form a mortar, so that a pliable mass is obtained, which is poured on top of the material E and left to dry, whereby the cement becomes hard. The cover thus formed on the porous cup is not affected by heat, acids, or other 95 substances frequently used in connection with batteries.

The cover is provided with the usual openings to permit the gases generated in the porous cup to escape. The apertures in the wax covers heretofore used are generally liable to become closed when the battery is exposed to heat by the softening of the wax, and when so closed the gases below the cover cannot escape and render the battery ineffective 100.

and dangerous. Heretofore metal and glass tubes were often inserted in the wax cover, so as to ventilate the cup and prevent closing of the aperture; but with my improved cover 5 I do not need any tubes whatever. The zinc electrode is placed in the jar in the usual manner.

Having thus fully described my invention, I claim as new and desire to secure by Letters 10 Patent—

1. In a porous-cup battery, the combination, with the porous cup, of a carbon electrode having inclined sides and placed with its base downward, and the electro-negative material

15 placed in the said porous cup and packed against the inclined sides of the carbon electrode, substantially as shown and described.

2. In a porous-cup battery, the combination, with a porous cup, of the electro-negative material placed in the said cup, an electrode having inclined sides and resting with its base on the bottom of said porous cup, and a cement cover held firmly on the mouth of the said porous cup by indentations in the latter which 25 are filled by the cement, substantially as shown and described.

3. In a porous-cup battery, the jar A, the lid G, fitting on the mouth of the said jar, and

the porous cup B, placed in the said jar and having indentations on the inside of its upper 30 end, in combination with the electro-negative material E, placed in the said cup B, the electrode C, having inclined sides which are in contact with the material E, and the cement cover F on top of the said material E and held 35 in place by the said indentations in the porous cup, substantially as shown and described.

4. In a porous-cup battery, a cover having apertures and formed of mortar or cement mixed with water and applied in a moistened 40 state and left to dry and harden, substantially as set forth.

5. In a porous-cup battery, a porous cup, electro-negative material placed in the said cup, and the electrode C in the said cup, in 45 combination with a cover having apertures and formed of mortar or cement mixed with water and applied in a moistened state and left to dry and harden on the mouth of the said cup and on top of the said negative material, substantially as set forth. 50
